(57) **CLAIM**

The ornamental design for the cordset assembly, as shown and described.

DESCRIPTION

FIG. 1 illustrates a top isometric view of a cordset assembly, according to our new design.

FIG. 2 illustrates a bottom view thereof.

FIG. 3 illustrates a lateral view thereof.

FIG. 4 illustrates a plug end thereof; and,

FIG. 5 illustrates a receptacle end thereof.

The features shown and described also encompass mirror images that are not necessarily shown and described.

The broken line portions of the Figures are included to show unclaimed subject matter only and formed no part of the claimed design.
